UNITED STATES PATENT OFFICE.

PATRICK J. DINN, OF ROXBURY, MASSACHUSETTS.

BARREL-HEAD FASTENER.

1,272,020.

Specification of Letters Patent.

Patented July 9, 1918.

Application filed July 17, 1916. Serial No. 109,618.

To all whom it may concern:

Be it known that I, PATRICK J. DINN, a citizen of the United States, residing at Roxbury, county of Suffolk, State of Massachusetts, have invented an Improvement in Barrel-Head Fasteners, of which the following description, in connection with the accompanying drawing, is a specification, like characters on the drawing representing like parts.

This invention relates to a novel improvement in barrel-head fastenings and is adapted to provide a means so that the head may be removed from a barrel without destruction of the component parts whether the head segments, staves or hoops. At present in opening barrels, the head-boards are simply hammered in, destroying the head-boards and often the staves, or, the hoops 20 which surround and hold the staves together are cut or hammered off. Such hoop removal allows the stave ends to spread apart so that the head-boards or segments are knocked out of the annular interior V-shaped groove of the barrel. These opening processes are time and labor consuming and destruction of the barrels usually results.

This invention contemplates the provision of a simple removable locking means to lock 30 one of the head-boards in position after the others have been properly positioned. Upon the removal of the locking or key-board the whole head is easily removed, without impairment of the barrel parts or displacement 35 of the hoops, so that the barrel content may be readily taken out as desired and the barrel may be again employed as a container. By the employment of this novel organization not only is destructive hammering and 40 hoop-knocking with its resultant injurious effect upon the barrel content obviated, but, the barrel itself is preserved, an important factor at present in view of the present scarcity in supply.

The general object of this invention is therefore to provide a simple, inexpensive and efficient fastening device for barrel-heads.

A more specific object is the production 50 of a novel barrel-head fastening means which is quickly removable without impairment of the barrel parts.

Other objects of the invention will more fully appear from the following description 55 and the accompanying drawings and will be pointed out in the annexed claims.

In the accompanying drawings, there has been disclosed a structure designed to carry out the objects of the invention, but it is to be understood that the invention is not confined to the exact features shown, as various changes may be made within its reasonable scope.

In the drawings, Figure 1 is a plan view of a barrel-head with the improved device thereon;

Fig. 2 is an enlarged detail view of the plate secured to a barrel-head board, looking at the underside thereof;

Fig. 3 is an enlarged section on the line 70 3-3 of Fig. 1;

Fig. 4 is an enlarged underside view similar to Fig. 2, but showing modified form;

Fig. 5 is an enlarged sectional view on the line 5-5, Fig. 4;

Fig. 6 shows an enlarged plan view of another modified form;

Fig. 7 is an enlarged sectional detail on the line 7-7, Fig. 6.

There has been disclosed in connection 80 with this novel barrel-head fastener, the usual type of sugar or flour barrel though obviously such improvement is adapted to be used in connection with variant types of barrels. The barrel here shown is composed 85 of a plurality of staves 1 of the ordinary type. These staves are interiorly grooved adjacent their ends so that, in the assembled form, there is provided an interior, annular V-shaped groove 2. This barrel-head comprises, as is usual, a number of segments or boards 3 of different lengths. The respective ends of these boards are cut in portions of an arc to conform to the interior of the assembled barrel staves and are generally 90 beveled to produce V-shaped edges in order more perfectly to fit in the similarly formed annular groove in the interior of the assembled barrel. A plurality of hoops are circumferentially placed about various parts of the barrel in the well-known manner and function to embrace and to retain the staves 1 together. The hoop 5 is one of such hoops and is shown in the drawings adjacent the stave ends. At present in placing the barrel-head on the assembled barrel, the shorter head segments or boards 3 are first positioned. Their V-shaped ends or sides are inserted in the interior annular V-shaped groove adjacent the barrel end and the 100 boards are transversely hammered into position. The usual central board 4 is posi-

105
110

tioned last, one end being inserted in the groove while the other end is downwardly knocked and wedged into the groove. The staves are usually slightly bowed to form a 5 barrel of greater diameter at its middle and hence, to release the pressure adjacent the barrel head during the heading operation, the end hoops are pushed toward the lessened diametered barrel ends and, after such 10 operation, are again driven into position.

In this novel organization, the usual central or key-board 4 is cut off or shortened at one end. This shortened end 6 is substantially squarely cut off as in the form 15 shown in Figs. 2 and 3, and it therefore falls short of the opposingly presented portion of the interior groove 2 of the assembled barrel. A novel plate 7 is removably secured to this key-board 4 adjacent the 20 shortened end 6. This plate, in this form consists of preferably a metallic material, pressed steel being at present employed. The plate 7 is made, as shown in the first 25 five figures, of a width substantially equal to that of the key-board 4 here shown as the central board though others suitable so to function may be selected. The plate extends a relatively short distance, as graphically disclosed, along the length of the key-board and is removably secured thereto as 30 by means of a screw 8. This plate is provided with a lip 9 which bears an angular relation to the major portion of the plate. This angular lip 9 is, as shown, downwardly 35 turned and transversely curved to conform to the arc of curvature of the opposingly presented, annular groove 2 of the barrel. This angled plate structure, in conjunction with the shortened head member or key-board 40 which it overhangs, functions to afford the demountable closure for barrel heads.

In assembling, this lipped plate is screwed to the key-board 4. The side boards of the barrel-head are knocked into position and 45 the V-shaped end of the key-board 4 is inserted in the barrel groove. The key-board is then downwardly dropped, whence the metallic curved lip of the plate rests upon the stave end adjacent the groove. A few 50 raps of a mallet or similar article serves to wedge firmly the overhanging metallic angular lip in the interior annular groove of the barrel. After such positioning of the head boards, the previously loosened end 55 hoop or hoops of the barrel are driven into place. Thus a firm, durable and efficient closure of a barrel end is readily effected.

The greater value of this novel structure is in the ease and simplicity with which the 60 barrel head is removed without impairment of any of the barrel parts. To remove the head, the screw 8, which functions to secure the plate to the key-board, is first unscrewed and removed when the plate may be lifted 65 from the key-board. The key-board 4 may

then be grasped by the fingers and removed without cutting or displacement of the barrel hoops. When this board is out of the way the other boards may easily be removed. It is therefore apparent that the plate and 70 pieces or boards comprising the barrel head are removable without destruction or impairment and may be again employed for the same function; that the hoops and barrel structure are preserved unharmed for 75 subsequent use; and that liability of injury to the contents of the barrel, as often occurs in the case of packing barrels containing fragile articles, is obviated.

In Figs. 4 and 5 there has been disclosed 80 a slight modification of this novel structure. Therein, the key-board 4 is not shortened to such a degree as in Figs. 1, 2 and 3; and, further, the shortened end, as shown in the underside view in Fig. 4, is made to curve 85 in an arc conformable to the inner face of the barrel. This construction is desirable in some cases where it is advantageous to obviate the space in the head caused by the fore-shortened key-board segment. In this 90 modified type the cover emplacement and removal are effected as in the first-mentioned device. There may be employed, as is common, an annular closure such as a hoop 10 which is placed on the outside of the head and which functions as a sealing means, but this is optional and is not essential in the 95 cases of barrels headed by this novel means.

Another modification is shown in Figs. 6 and 7. Therein, the angular portion 9 100 is of less width than the major portion of the plate. Such plate structure is used in conjunction with various widths of head boards. Of the forms shown, this type of plate is that of greatest utility, in view of 105 its adaptability to different head segments employed as key-boards. In this preferred type the lip 9 does not extend transversely the whole width of the front edge of the plate but preferably extends at least its 110 major portion. In Fig. 6 such a form of the invention is shown as secured to a key-board of greater width than the lip 9. The 115 lip effects, as in the other types, the wedging function with the barrel groove while the portions 11 of the front edge of the plate are transversely curved in an arc and are of such dimension as forcibly to bear against the barrel inside, adjacent the upper end of the groove, and thus to achieve 120 complete closure of the barrel at these points. The lateral portions of this plate extend over the adjacent head-boards 3 overlapping the same. The fastening media need not be a single screw passed 125 through an ear in the plate, but, as shown in Fig. 6, such media may consist of one or more screws passed through the body portion of the plate.

In Fig. 7 there has been disclosed a type 130

of bolt and nut which has proved advantageous in use. In this form the nut 12 is provided with prongs 13 which are embedded in the board used as the key-board. 5 These prongs function to hold the nut securely to the underface of the key-board and to prevent its dropping off into the barrel interior when the bolt is removed preparatory to taking off the plate. The bolt 10 is threaded adjacent its lower end and is passed through apertures in the plate and key-board and is received in threaded engagement with the nut 12.

There has thus been provided a simple, 15 efficient and inexpensive barrel-head fastener which effects the complete closure of a barrel and securely locks the head in such position. It is easily and quickly removed so that the barrel-head may be expeditiously opened without impairment or injury to the barrel content or to the barrel parts themselves. It is not even necessary to remove or displace the barrel hoops adjacent the head end. Through the employment 20 of this device the saving in barrel costs is great as they may be re-used repeatedly.

It is to be understood that the construction disclosed herein is illustrated but not 30 restrictive and that the same may be modified within the meaning and scope of the claims which follow.

Having fully described my invention, 35 what I claim as new and desire to secure by Letters Patent is:

1. The combination of a barrel having an interior annular groove adjacent the head end; head-members having portions formed to engage the groove; a key-member having 40 one end formed to engage said groove; a

plate demountably secured to the key-member at its other end; a lip formed on the central major portion of the edge of the plate and engaging the said barrel groove, the remainder of the edge of the plate being 45 formed to rest against the barrel adjacent the groove whereby the plate may be secured to key-members of greater width than the lip and a locked closure is provided for the barrel. 50

2. The combination of a barrel having an interior annular groove adjacent the head end, head-members having portions formed to engage the groove, a key-member having one end formed to engage the groove, a 55 plate on the other end portion of the key-member, a terminal lip on said plate angularly projecting therefrom and adapted to engage the barrel groove and thereby lock the head and key-member in barrel closing position. 60

3. The combination of a barrel having an interior annular groove adjacent the head end, head-members having portions shaped 65 to engage the barrel groove, a key-member having one end portion terminating in an edge shaped to engage the groove and the other end terminating in a substantially straight edge, and a locking plate removably secured to the key-member adjacent 70 its straight edged end and projecting downwardly therebeyond to engage the barrel groove, the straight edge of the key-member affording a space between the key-member and the barrel interior whereby 75 the key-member may be easily disengaged upon removal of the locking plate.

In testimony whereof I have signed my name to this specification.

PATRICK J. DINN.
